COMBINED WINDOW REGULATOR AND
DOOR LATCH OPERATORHolden W. Rightmyer, Toledo, Ohio, assignor to
The American Swiss Company, Toledo, Ohio, a
corporation of Ohio

Application December 23, 1935, Serial No. 55,734

4 Claims. (Cl. 268—126)

This invention relates to vehicle window regulators and door latches, but more particularly to a device for selectively actuating the window regulator mechanism or door latch mechanism.

- 5 An object is to produce a single control for selectively operating a vehicle window regulator or a door latch which is simple in construction, inexpensive to manufacture and utilizes a single handle, which is actuated in the conventional manner for operating the regulator mechanism and enables operation of the door latch mechanism by depression of a push button or the like without disconnecting the handle from the regulator mechanism.
- 10 15 Another object is to produce an operating mechanism for a window regulator and a door latch embodying a single operating handle which is rotated in the usual manner for operating the regulator, but which upon actuation of the control element affords actuation of the latch mechanism without disconnecting the handle from the regulator mechanism by utilizing lost motion provided in the regulator mechanism.

20 A further object is to produce an operator of this character having the new and improved features of construction, arrangement, and operation hereinafter described, and for purposes of illustration, but not of limitation, embodiments of the invention are shown on the accompanying drawings, in which:

25 Figure 1 is a side elevation of a portion of a door embodying a regulator mechanism attached to a vehicle window, a door latch mechanism and showing the single control for selectively operating these mechanisms;

30 Figure 2 is an enlarged sectional view on the line 2—2 of Figure 1 showing the control elements;

35 Figure 3 is a perspective view of the plunger element;

40 Figure 4 is a transverse sectional view on the line 4—4 of Figure 2;

45 Figure 5 is a sectional view similar to Figure 2 showing the plunger in depressed position for actuating the door latch;

50 Figures 6, 7 and 8 are sectional views showing the latch operating arm and a portion of the remote control strap in normal position, bolt retracted position and dogging position, respectively;

55 Figure 9 is an enlarged sectional view on the line 9—9 of Figure 7;

Figure 10 is a sectional view on the line 10—10 of Figure 7 showing the connection between the latch retracting arm and link; and

Figure 11 is an elevation showing an alternate form of control mechanism.

The illustrated embodiment of the invention comprises a door 10, which may be the door of an automobile body having the usual side window opening (not shown) which is adapted to be closed by the usual glass panel or window 11 to the lower edge of which are mounted retainers 12. The retainers 12 are provided with longitudinally elongate horizontal guides or channels 13 to receive the usual studs 14 mounted on the free ends of the regulator arms 15. The opposite ends of the arms 15 are fixed to studs 16 pivotally mounted in a back plate 17 which is suitably secured to the door 10. Spiral springs 18 having one end fixed to the studs 16, and the opposite end secured to the back plate, counterbalance the weight of the window in the usual manner. Fixed to each of the arms 15 is a gear sector 19, which mesh with each other, one of the gear sectors 19 meshing with a pinion 20, forming part of a clutch mechanism.

The clutch mechanism comprises a U-shaped driven part 21 to which the pinion 20 is fixed and a substantially V shaped driver 22 having each end portion disposed between the legs of the U shaped member 21. Enclosing the parts 21 and 22 is a clutch housing 23, and disposed between the legs of the U shaped driven member and the inside walls of the housing is a helically coiled spring 24 having inturned ends 25 disposed between a leg of the driving member 22 and a leg of the driven member 21.

From an inspection of Figure 4, it will be apparent that turning movement of the driving member in either direction operates to contract the spring 24 and allow it to move with the driving and driven members, a limited amount of lost motion being available between the driving member 22 and the driven member 21, and such lost motion is made use of in the actuation of the door latch as will hereinafter appear. It will be understood that retrograde movement of the pinion 20 is prevented by the clutch, since movement of the driven member 21 in either direction tends to expand the spring 24 against the walls of the housing 23.

It is to be understood that the regulator mechanism above described and the clutch mechanism are old in the art, and do not form any part of the present invention, such showing being merely illustrated to enable the operating mechanism to be clearly understood.

In accordance with this invention a gear 26 is disposed on the outside of the clutch housing 23

and is fixed to the driving member 22 for turning movement therewith. Heretofore an operating handle has been fixed for turning movement with the driving member 22. Consequently, it is possible to adapt clutch mechanisms heretofore in use by changing only the driving member 22, by securing thereto the gear 26 instead of the usual squared shank to which the handle was ordinarily attached.

10 The gear 26 meshes with a similar gear 27, which is secured to a stud 28 and extends outwardly through the door trim 29 to receive an operating crank handle 30 which is fixed to the stud 28 by a key 31. The hub of the handle is shouldered to receive the usual escutcheon 32. It will be apparent that through the connections described, turning of the handle imparts swinging movement in opposite directions to the regulator arms 15, thereby to raise or lower the window 11, as desired, such operation being the usual manner of actuating the regulator mechanism.

As will hereinafter appear, the handle 30 may also be employed to actuate the door latch mechanism, and although numerous forms of latch mechanisms may be employed, one example is shown on the accompanying drawings. The latch mechanism comprises a back plate 33, which is suitably secured to the door adjacent one vertical edge thereof and mounted thereon is a latch bolt having a nose 34, which, when in latching position, projects outwardly from the edge of the door. The nose 34 is fixed to a bolt plate 35 which is formed with an outwardly projecting ear 36. A spiral spring 37 urges the bolt nose to latching position. The latch bolt may be retracted from the outside of the door by the usual roll back 38 having a squared handle receiving opening 39. The roll back 38 may be dogged or held against movement by a slide 40, which may be actuated by a key operated cam 41, as will readily be understood by those skilled in this art.

For retracting the latch bolt from the inside of the door, a slide 42 engages the outer surface of the bolt plate 35 and has a projection 43 engageable with the ear 36 upon rearward movement thereof for retracting the bolt against the force of the spring 37. The slide 42 may be moved forwardly relative to the bolt, so that a projection 43 thereof may be disposed beneath an arm 44 of the roll back 38 for dogging the latter.

For actuating the slide 42, a remote control link 45 is pivoted at one end to the rearward end of the slide and extends rearwardly therefrom, terminating in a downturned rear end portion 46 formed with an elongate slot 47 to receive the head 48 of a rivet 49 secured in the upper end portion of an arm 50. The head 48 has a lateral extension 51, which is disposed horizontally or at substantially right angles to the slot 47 in the remote control link 45. This structure enables the latch mechanism, which is assembled as a unit with the remote control link 45 in position, to be connected to the arm 50 in a simple and convenient manner, it being merely necessary to fit the slotted end portion of the link over the lateral extension 51 of the rivet, and then turn the remote link to the desired horizontally disposed position. A spring washer 52 is disposed between the downturned portion 46 of the remote control link and the arm 50 to eliminate rattles.

The opposite end of the arm 50 is formed with a polygonal opening to fit over a nut 53 for movement therewith. The nut 53 has a sleeve-like extension 54 which extends through and has bearing in an opening formed in a cover plate 55, a

plate 56 fixed to the outside of the cover plate for closing the opening. The cover plate 55 is formed with ears 57, which project through openings in an extension plate 58 which is secured by rivets 59 to the regulator back plate 17. Formed on the opposite side of the nut 53 is an annular sleeve-like portion 60, which is recessed to receive fingers 61 which are integral with and depend from the stud 28. Disposed normally between the fingers 61 is a head 62, generally oval in shape, which is secured to a stem 63. The stem 63 extends axially through the stud 28 and hub of the handle 30, the outer end portion being disposed within a socket 64 provided in the hub of the handle 30. The outer end of the stem 63 is formed with screw threads 65 to receive a button 66 and disposed between the undersurface of the button 66 and the bottom of the socket 64 is a coil spring 67. As shown, the button 66 is formed with a plurality of peripheral notches 68 to receive a special tool to enable the button to be unscrewed from the stem.

Formed in the nut 53 below the sleeve extension 60 is a cavity 69 which is formed with an annular row of serrations 70. The head 62 of the plunger stem 63 has its opposite ends so shaped as to fit between pairs of serrations 70 so that upon depression of the button 66 the head 62 will be forced to a position such that its opposite ends will be disposed between opposed pairs of serrations 70, although a portion of the head will be disposed between the fingers 61. When in this position (such as shown in Figure 5) turning movement of the handle 30 will impart corresponding movement not only to the stud 28 but to the nut 53 through the fingers 61 and plunger head 62, thereby imparting longitudinal movement to the remote control link 45 through the arm 50 in one direction or the other.

Upon movement of the arm 50 in a counter-clockwise direction, the latch bolt will be withdrawn by the slide 42 in the manner above described. Upon movement of the arm 50 in a clockwise direction the slide 42 will be moved forwardly into position to dog the roll back 38. As above mentioned, sufficient lost motion is provided in the driving clutch for the regulator mechanism to enable the stud 28 to move in one direction or the other to effect such latch retracting or dogging movement to the latch mechanism.

Formed on the outer surface of the arm 50 are depressions 71 into which a leaf spring 72 having one end anchored to the cover plate 55 is adapted to snap for retaining the arm 50 in normal position with the latch bolt projected or in its forward position in which the slide 42 has been moved to dogging position.

The form shown in Figure 11 is similar to that above described, except that in place of the arm 50 an arm 50a has a toothed connection 50b with an arm 50c which is pivoted intermediate its ends at 50d. This enables the remote control link 45a to which one end of the arm 50c is connected to be actuated in a direction opposite to that of the arm 50 by a similar movement of the operating handle 30a. For example, movement of the handle 30 in Figure 1 in one direction will operate to retract the latch bolt, whereas movement of the handle 30a in Figure 11 in the same direction operates to move the slide 42 to dogging position. Other features of this form of mechanism are substantially the same as those above described.

It is to be understood that numerous changes

and details in construction, arrangement and operation may be effected without departing from the spirit of the invention, especially as defined in the appended claims.

5. What I claim is:

1. In a device of the class described having a window regulator provided with a spring clutch having a limited amount of lost motion and a door latch, a gear for operating the regulator through the clutch, a regulator operator having a gear constantly in mesh with said first gear, a handle fixed to said regulator operator, a door latch operator adjacent said regulator operator, a connector operable independently of said handle from a point adjacent said handle for connecting said regulator and latch operators to enable conjoint movement thereof, thereby enabling operation of the latch through said lost motion without operating the regulator, said handle being mounted for rotational movement but held against movement in other directions.

2. In a device of the class described having a window regulator provided with a spring clutch having a limited amount of lost motion and a door latch, a gear for operating the regulator through the clutch, a regulator operator having a gear constantly in mesh with said first gear, a handle fixed to said regulator operator, a door latch operator adjacent said regulator operator, a connector operable independently of said handle from a point adjacent said handle for connecting said regulator and latch operators to enable conjoint movement thereof, thereby enabling operation of the latch through said lost motion without operating the regulator, said handle being mounted for rotational movement but held against movement in other directions.

motion without operating the regulator, said connector comprising a spring pressed plunger having a head at one end movable into engagement with both of said operators.

3. In a device of the class described having a window regulator provided with a spring clutch having a limited amount of lost motion and a door latch, a gear for operating the regulator through the clutch, a regulator operator having a gear constantly in mesh with said first gear, a handle fixed to said regulator operator, a door latch operator adjacent said regulator operator, and a pin extending coaxially of said handle and regulator operator, a head on said pin adapted to be moved into engagement with both operators, and a spring normally holding said head out of operative engagement with said latch operator.

4. In a mechanism for selectively operating a window regulator provided with a two-way clutch having a limited amount of lost motion and a door latch, a single operating handle mounted for rotational movements but held against movements in other directions, an operating connection constantly established between said handle and regulator for imparting movements thereto through said clutch upon rotation of the handle in one direction or the other, operating means for said door latch, and control means operable independently of said handle for establishing an operative connection between said handle and latch operating means through the lost motion of said clutch without imparting movement to said regulator.

HOLDEN W. RIGHTMYER.
